UNITED STATES PATENT OFFICE.

JAMES L. LEE, OF CHICAGO, ILLINOIS.

PRINTER'S BLOCK.

SPECIFICATION forming part of Letters Patent No. 586,557, dated July 20, 1897.

Application filed July 16, 1896. Serial No. 599,386. (No model.)

To all whom it may concern:

Be it known that I, JAMES L. LEE, a citizen of the United States, residing at Chicago, in the county of Cook and State of Illinois, have 5 invented certain new and useful Improvements in Printers' Blocks, of which the following is a full, clear, and exact specification.

My invention relates to printers' blocks for holding electrotypes and other printing-plates 10 in the form while being printed from. It has more especial reference to that class of printers' blocks in which the plate is held on one side by any suitable means, such as a salient flange or edge, which is usually formed on a 15 separate piece, and on the other side by an adjustable jaw adapted to be forced against the plate by means of a screw having a pinion for the engagement of a hand rack-bar, by which the screw may be turned. This pinion 20 for turning the screw has heretofore occupied much valuable space in the form, owing to the fact that it must be arranged on one side or end of the block, so as to be exposed for the engagement of the hand rack-bar, and 25 when so arranged it is in the way of the clamping-jaw and prevents the same from receding entirely to the outer edge of the block, and hence makes it impossible to hold a plate that is the full area of the block-surface. The said screw which carries the pinion 30 is usually journaled at its inner end in the block itself, while its outer end in the construction heretofore employed is journaled in a brass or other soft-metal plate secured to the end of the block, such plate necessarily being of soft metal in order that it 35 may be dressed down uniformly with the type-metal, of which the block is usually composed.

The object of my present invention is to 40 move the pinion outwardly or substantially flush with the outer plane of the said end plate, whereby the space occupied by the thickness of the bearing for the screw heretofore formed in the end plate may be added 45 to the outward movement of the clamping-jaw; or, in other words, the object of my invention is to carry the pinion farther away from the block proper without thickening the end plate and without depriving the screw of 50 its proper bearing in the end plate.

With these ends in view my invention con-

sists in certain features of novelty in the construction, combination, and arrangement of parts by which the said objects and certain other objects hereinafter appearing are attained, all as fully described with reference to the accompanying drawings, and more particularly pointed out in the claims.

In the said drawings, Figure 1 is a vertical longitudinal section of my improved device, 60 taken on the line 1 1, Fig. 3. Fig. 2 is a transverse section taken on the line 2 2, Fig. 1. Fig. 3 is an end view looking toward the pinion and end plate. Fig. 4 is a plan view; and Fig. 5 is a transverse sectional view taken 65 on the line 5 5, Fig. 1, the clamping-jaw being omitted from the section.

1 represents the block proper, which is constructed of any suitable material, such as type-metal, and which, as heretofore, is reduced on its under side, as shown at 2, for the sake of lightness and also for permitting of the reciprocating movement of the clamping-jaw 3, which is provided with a shank working through a longitudinal slot 4, formed 75 through the face of the block 1.

5 represents the screw, which operates the jaw 3, as usual, and which has its inner end journaled in the end of the block 1 in any suitable manner, while its outer end is provided with the pinion 6, formed thereon or rigidly secured thereto, as usual.

7 represents the end plate, constructed of brass or other suitable material and secured to the block proper, 1, in any suitable manner, such as by means of the horizontal bolts or screws 8, the face and upper edge of the plate 7 being provided with a rabbet 7*.

The outer end of the screw 5 in the constructions heretofore employed is made to 90 project through the pinion 6 and is journaled outside of the pinion in the end plate 7, but in my invention the pinion 6 is located on the extreme end of the screw 5, as shown more clearly in Fig. 1, and the end plate 7 has its 95 outer surface mortised or cut away on the circular line 9, so as to receive the pinion and be flush with the vertical plane thereof. By this means I carry the inner surface or plane of the pinion as much farther from the jaw 100 3 than heretofore as the space heretofore occupied by the thickness of the metal in the

plate 7, utilized as a bearing for the screw 5. In order that the screw 5 may still have a firm and substantial bearing without obstructing the movement of the jaw 3, I let 5 into the inner face of the end plate 7 a steel or other suitable bushing 10, which forms a bearing for the screw 5. The upper side of this bushing 10 is cut away, as shown at 11, so as to permit the shank of the jaw 5 to recede 10 until it strikes against the pinion 6, while the under side of such bushing is provided with a slot 12, which fits over a reduced journal 5^a of the screw 5 in the manner shown in Fig. 2. By this means the screw 5 is rigidly held 15 against any lateral or upward movement, these being the directions in which substantially all of the transverse strain on the screw is produced. The screw is held against downward movement in the slot 12 by the pinion 20 6, resting upon the lower side of the mortise or recess 9. The screw is held against inward longitudinal movement by a shoulder 13, formed thereon, and also by the plate or bushing 10, against which the inner face of 25 the pinion may abut, and it is held against outward longitudinal movement by means of a shoulder or flange 14, formed on the screw and being of sufficient diameter to overlap the slot 12 in the plate 10, as shown more 30 clearly in Figs. 1 and 5.

In order that the bushing or plate 10 may not increase the thickness of the plate 7 or occupy space necessary for the movement of the jaw 3, such plate or bushing 10 is let into 35 the inner face of the end plate 7, a circular recess or mortise being formed in the plate 7, as indicated by full lines in Fig. 2 and dotted lines in Figs. 3 and 5, and such mortise or recess being of slightly greater diameter 40 than the recess 9, whereby a shoulder or flange is formed for supporting the bushing or flange on the inner side, the bushing being held in place on the other side or side next the block 1 by the end of such block. The end plate 7 45 on each side of the cut-away portion 11 is carried over the upper edge of the bushing 10, as shown at 15, and crowded downwardly, so as to hold such bushing against rotation.

It will of course be understood that rotation 50 is imparted to the pinion-wheel 6 in the ordinary manner well known to printers—that is to say, by means of a rack-bar having a suitable handle and teeth capable of engaging with the teeth of the wheel 6 at its upper 55 edge, where it protrudes above the rabbet 7^a. The point of the jaw 3 is never at any time sufficiently projected over the wheel 6 to prevent the operating rack-bar from engaging 60 with the teeth of the wheel, although at times it may be necessary to slightly tilt the rack-bar away from the jaw.

Having thus described my invention, what

I claim as new, and desire to secure by Letters Patent, is—

1. A printer's block having in combination 65 the block proper, the clamping-jaw, a screw journaled at one end in said block for moving said jaw and having a shoulder thereon, a pinion for turning said screw, the end plate recessed for the reception of said pinion, and 70 a bushing forming a bearing for said screw and being interposed between said pinion and shoulder, substantially as set forth.

2. A printer's block having in combination 75 the block proper, the clamping-jaw, a screw for moving said jaw, having a shoulder, a pinion on the extreme end of said screw, the end plate having a recess in its outer surface receiving said pinion, and a bushing interposed between said end plate and block 80 proper and forming an abutment for said shoulder, substantially as set forth.

3. A printer's block having in combination 85 the block proper, the clamping-jaw, the screw for moving said jaw, having a shoulder or reduced journal, a pinion secured to the end of said screw, the end plate having a mortise in its outer surface receiving said pinion and a slotted bushing embracing said reduced journal and being let into the inner face of 90 said end plate, substantially as set forth.

4. A printer's block having in combination 95 the clamping-jaw, a screw having a pinion on one end thereof, said pinion being let into a recess in the outer wall of the printer's block and said screw being provided with a shoulder, and a bushing embracing said screw between said shoulder and pinion and being inserted into the printer's block at the inner side or face of said pinion, substantially as 100 set forth.

5. A printer's block having in combination 105 the block proper, the clamping-jaw, the screw for moving said jaw, having a shoulder thereon, an end plate having a recess in its outer face, a pinion let into said recess and being secured to said screw, a bushing interposed between said end plate and block proper and having a slot extending through its periphery and embracing said reduced journal, sub- 110 stantially as set forth.

6. A printer's block having in combination 115 the block proper, the clamping-jaw, a screw for moving said jaw, an end plate having a recess, a pinion on said screw let into said recess, and a bushing interposed between said pinion and block proper and having a cut-away portion in its upper side for the passage of said clamping-jaw, substantially as set forth.
